LIQUID FUEL BURNER

Richard H. Pardee and Robert J. Strawn, Jr.,
La Junta, Colo.

Application October 27, 1952, Serial No. 317,019

3 Claims. (Cl. 158—53)

1

This invention relates to a liquid fuel burner, and more particularly to a burner designed for use with liquid propane and similar liquid gases for throwing a flame for use in weed burning.

The principal object of the invention is to provide an exceedingly simple burner construction which will efficiently vaporize and gasify liquid fuels such as propane and butane, and which will completely burn the fuel to produce an exceedingly hot high velocity flame.

Another object of the invention is to provide a burner for weed burning purposes that will be light in weight, so as to be easily portable.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a side view of the improved burner;

Figs. 2 and 3 are enlarged cross-sections through the burner, taken on the lines 2—2 and 3—3, respectively, Fig. 1;

Fig. 4 is a longitudinal section through the burner on the original scale, taken on the line 4—4, Fig. 3;

Fig. 5 is an enlarged, detail section through the forward upper peripheral edge of the burner taken on the line 4—4, Fig. 3; and

Fig. 6 is a detail, longitudinal, sectional view through a fuel orifice bushing employed in the improved burner.

The improved burner comprises an elongated tubular combustion chamber 10 having an open forward extremity. The rear extremity of the combustion chamber is closed by an annular end plate 11. A tubular fuel expansion chamber 12 communicates concentrically through the end plate 11 in axial alignment with the chamber 10. The forward extremity of the expansion chamber 12 is open to the combustion chamber 10, and the rear extremity of the former is closed by a circular end plate 13.

A vaporizing jacket 14 surrounds the forward extremity of the combustion chamber 10. The jacket 14 is enclosed in a cylindrical outer housing 15 which is uniformly spaced from the wall of the chamber 10. The rear extremity of the jacket 14 is closed by an annular rear wall 16, and the forward extremity thereof is closed by

2

a circular pipe ring 17, welded or otherwise secured therein to seal the vaporizing jacket 14.

Liquid fuel, such as liquid propane, is conducted to the pipe ring 17 by means of a feed pipe 18 extending through the rear wall 16 of the housing 15 and terminating at its forward extremity in communication with the pipe ring 17. The rearward extremity of the feed pipe 18 is spaced from the wall of the combustion chamber 10 and provided with any suitable hose coupling 19 to which a conventional fuel hose may be connected.

The pipe ring 17 is provided with a plurality of spray perforations 20 which enter the pipe ring on a conical angle with reference to the circumference of the pipe ring 17 so that the jets of fuel discharging from the perforations 20 will be directed at an inward angle against the wall of the combustion chamber 10, as shown in Fig. 5.

Vapor is conducted from the jacket 14 by means of a hook-shaped vapor pipe 21 which communicates through the rear wall 16 of the housing 15 and extends rearwardly to a hook-shaped extremity 22. The latter extremity curves inwardly through the end plate 13 where it is sealed into a coupling sleeve 23 welded or otherwise mounted in the latter plate.

A threaded jet bushing 24 is threaded into the inner extremity of the coupling sleeve 23. The inner extremity of the jet bushing 24 is closed, and the closure is perforated by means of an angularly positioned fuel orifice 25 which enters at an acute angle to the axis of the latter so that vapors and gases discharging from the orifice 25 will be directed on a spiral path against the wall of the expansion chamber 12.

Primary air enters the combustion chamber 10 through a plurality of air openings 26 positioned in and adjacent the end plate 11, and secondary air enters the combustion chamber through a plurality of similar openings 27 positioned forwardly of the openings 26. The air openings are carefully predetermined as to area to obtain the most efficient combustion.

In use, a liquid fuel hose is connected to the coupling 19. The fuel feeds into the pipe ring 17 and discharges from the latter in a plurality of jet-like streams directed inwardly against the hot wall of the combustion chamber 10. The heat of the latter immediately vaporizes and gasifies the fuel, creating a pressure in the jacket 14. This pressure forces the vaporized fuel through the vapor pipe 21 and discharges it from the orifice jet 25 at exceedingly high velocity on a whirling, angular spiral path.

The discharging vapors swirl at high velocity from the expansion chamber 12 in a highly vaporized condition. This whirling, high-velocity vapor swirls through the combustion chamber 10 on a spiral path, picking up combustion air through the openings 26 and 27 and discharging from the open forward extremity of the burner as a high-velocity, high-intensity flame.

The hook-shaped vapor pipe 21 provides a convenient handle for carrying the burner, and also provides a convenient attachment for attaching the burner to the supporting bars of railway burner cars and other carrying vehicles. No pumps or compressors are necessary with the improved burner, since the pressure generated in the chamber 14 is sufficient for complete burner operation.

The combustion chamber 10 may be strengthened and stiffened from the outer housing 15 by means of suitable spacer members 28 welded or otherwise mounted in the vaporizing jacket 14.

While a specific form of the improvement has been described and illustrated herein, it is to be understood that the same may be varied, within the scope of the appended claims, without departing from the spirit of the invention.

Having thus described the invention, what is claimed and desired secured by Letters Patent is:

1. A liquid hydrocarbon fuel burner comprising: a tubular combustion chamber having an open forward extremity; an annular end plate closing the rearward extremity of said chamber; a tubular expansion chamber of smaller diameter than said combustion chamber communicating centrally through said end plate and extending rearwardly in axial alignment with said combustion chamber; a rear end plate closing the rear extremity of said expansion chamber; a sealed, annular vaporizing jacket surrounding the forward extremity of said combustion chamber; a

pipe ring closing the forward extremity of said jacket; an annular ring plate closing the rear extremity of said jacket; a fuel feed pipe extending forwardly through said ring plate and terminating in communication with said pipe ring, said pipe ring having spaced perforations communicating with said vaporizing jacket; a vapor pipe communicating through the ring plate with the vaporizing jacket and extending rearwardly beyond said expansion chamber, thence forwardly to communicate through the rear wall of the latter chamber; an orifice member mounted in the rear wall of said expansion chamber in communication with said vapor pipe, there being air openings through the wall of said combustion chamber adjacent the rear extremity thereof.

2. A liquid hydrocarbon fuel burner as described in claim 1 in which the openings in said pipe ring are directed inwardly and rearwardly on a conical angle to direct the fuel discharging therefrom against the cylindrical wall of said combustion chamber.

3. A liquid hydrocarbon fuel burner as described in claim 2 in which the orifice in said orifice member is inclined at an acute angle to the axis of said expansion chamber so as to direct vapor against the inner wall of the latter.
